(57) **CLAIM**

The ornamental design for a hair processing accelerator, as shown and described.

DESCRIPTION

FIG. 1 is a front view of a hair processing accelerator in accordance with my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a cross sectional view taken along line A—A in FIG. 1;

FIG. 8 is a cross sectional cut showing the plane taken along line B—B in FIG. 4;

FIG. 9 is a perspective view thereof;

FIG. 10 is a front view of the hair processing accelerator shown with the heating units in an alternate position; and,

FIG. 11 is a perspective view of the hair processing accelerator shown with the heating units in another position.
